AUTOMOTIVE CHOKE TESTER OR SIMILAR ARTICLE

Renzo N. Rutili, Albert Lea, Minn., assignor to
Owatonna Tool Company, Owatonna, Minn.

Filed Oct. 27, 1972, Ser. No. 301,624

Term of patent 14 years

Int. Cl. D10—05

U.S. Cl. D52—6 R

FIG. 1 is a right front perspective view of an "automotive choke tester" showing my new design;

FIG. 2 is a top plan view thereof on an enlarged scale;

FIG. 3 is a left side elevational view thereof;

FIG. 4 is a front elevational view thereof;

FIG. 5 is a rear elevational view thereof.

I claim:

The ornamental design for an automotive choke tester or similar article, substantially as shown and described.
